UNITED STATES PATENT OFFICE.

WILLIAM E. WILLIAMS, OF CHICAGO, ILLINOIS.

MACHINE FOR ROLLING CAR-WHEEL TIRES.

SPECIFICATION forming part of Letters Patent No. 527,038, dated October 2, 1894.

Application filed September 21, 1892. Serial No. 446,457. (No model.)

To all whom it may concern:

Be it known that I, WILLIAM E. WILLIAMS, a citizen of the United States of America, residing at Chicago, in the county of Cook and

5 State of Illinois, have invented certain new and useful Improvements in Machines for Rolling Car-Wheel Tires, of which the following is a specification.

Referring to the accompanying drawings, 10 wherein like reference-letters indicate like parts: Figure 1 is a top plan; Fig. 2, a vertical section in line 2—2 of Fig. 1; Fig. 3, an end elevation; Fig. 4, a side elevation; Figs. 5 and 6, details of the parts that act directly 15 on the tire; and Figs. 7 and 8, details of a modification.

In rolling tires or rims for wheels to be used 20 on street-cars, hand-cars, and other light railway-carriages, the function of the rolling-machine is to transform a metal hoop or blank such as is shown in partial section at T (Fig. 5), into the form shown in partial section at T' (Fig. 6), by rolling up, at one edge, the outer flange t, and turning down, 25 at the opposite edge, the inner flange t'.

The object of my invention is to produce a machine by which these operations can be readily and conveniently performed; and the invention consists in the several mechanical 30 combinations herein described and more particularly specified in the claims.

In the drawings (see Fig. 1), F is the frame of the machine, and P the driving-pulley, from whose shaft power is transmitted by 35 bevel gears p p' to the shaft G of the exterior roll S, and thence by gear-wheels g h (see Fig. 2), to the shaft H of the interior rolls r r'. The annular tire-hoop or blank, is, during 40 the operation of the machine, gripped and held between the exterior roll S and the interior roll r; and it is therefore necessary that one or each of said rolls should be adjustable toward and from the other, to enable the blank to be inserted, gripped and 45 moved. I prefer to make the exterior roll stationary and the interior roll r adjustable for this purpose, and, accordingly, such is the form of machine, herein shown and described. In this form of the machine, the stationary 50 shaft G is mounted in bearings fixed to the frame F, and its roll S is substantially cylindrical and is provided with a circumferential

groove s' to aid in forming the outer flange t of the tire, while the interior rolls r r' are adapted to be moved toward and from the roll S.

As there are various known means by which one shaft or roll can be adjusted toward and from another, I do not limit myself to any specific form of device for adjusting the shaft H and its roll r, although I prefer the construction illustrated in the drawing wherein the end of the shaft H, remote from the rolls, is mounted in a rocking bearing h', and the end proximate to the rolls is 60 mounted in a movable sash or frame E (see Fig. 1), consisting essentially of a bearing-block e, a cross-head e' and two side-rods e² e² connecting the parts e e'. The sash is supported by the screw-rod E' and the sleeve e 70 and is prevented from lateral displacement by the sides of the opening in the table F within which closely fits said sash being adjusted by means of a screw-rod E' suitably mounted in the frame of the machine and 75 screwing through the cross-head so as to swing the roll-end of the shaft without disengaging the gears g h. One of the interior rolls r, (which may be termed the feed-roll), is cylindrical and concentrically fixed upon the 80 shaft H so as to partake of all the movements thereof, while the other, r' (which may be termed the flanging-roll), is provided with a large central opening through which the shaft H extends (see Fig. 2), and is adjustable toward and from the roll S independently of the above-described adjustments of shaft H and roll r, and is provided with a circumferential rib r² operating to press the tire-metal into the groove s' to form up the outer 85 flange t of the rim or tire. This use of two interior rolls, one of which is separately adjustable in its relations to the exterior roll, is the essential feature of my main invention. For the purpose of convenience and 90 labor-saving in the practical operation of the machine, I prefer to make the roll r' not only adjustable independently of, but also concurrently with, its companion roll r. To accomplish the independent adjustment of roll r', 95 it is necessary that it should have a central opening, r³, around shaft H, sufficiently large to permit such adjustment, and that it should be mounted on a special bearing adapted to 100

be moved by a different lever from that employed in adjusting roll r and its shaft. To accomplish, at the same time, the concurrent adjustment of rolls r r' , it is necessary that 5 the special bearing of roll r' should be supported by and movable with the sash E or other device for adjusting roll r , so that whenever roll r is adjusted roll r' will move with it, while roll r' can itself be moved without 10 moving roll r .

There are various forms of means in which these mechanical principles may be embodied, but I prefer the form illustrated in the drawings, (see Figs. 1 and 2,) in which the 15 roll r' is provided with an annular bearing-flange m mounted in a movable bearing-block M articulated at m' to a lever M' which in turn is articulated at m^2 to another lever M^2 that is connected by a fulcrum-pin m^3 to a 20 suitable lug formed on the sash E or bearing-block e. At the end of the levers M' M^2 opposite to the connection m^2 , the lever M^2 is articulated to a pin projecting from the side of a sleeve n held between collars n' on a rod 25 N, which extends loosely through the sleeve; while the other lever M' is similarly articulated to the side of a nut N' screwing upon the rod N. It follows that by turning the screw-rod E' both of the rolls r r' are adjusted 30 simultaneously and equally toward or from the roll S, while by turning the rod N the lever M' is operated and the roll r' is adjusted toward or from the roll S without disturbing the roll r . The rod N is made in two parts 35 connected by a link n^2 to enable its lower end to accommodate itself to the action of the levers, and is provided with a crank or turn wheel n^3 .

The operation of this machine, so far as 40 above described, is as follows:—In order to remove a completed tire from between the interior and exterior rolls, said rolls are separated, as shown in Fig. 2, by operating the rod E', and then, by an operation of the rod 45 N, the flanging-roll r' is moved still farther away from roll S to the position shown in Fig. 5, thereby withdrawing its rib from the flange and releasing the tire. The tire is then removed and a fresh hoop or tire-blank inserted 50 between the interior and exterior rolls, with its opposite side passing around a guide roll I (Figs. 2 and 4), and, by a movement of the rod E', is gripped firmly between the roll S and the feed-roll r , and thereby caused to be 55 rotated around its central axis. The attendant now operates rod N so as to bring the flanging-roll r' against the revolving hoop or blank and cause it to bend the metal into the groove s' , and he gradually increases this 60 bending pressure until, finally, roll r' is brought concentric to shaft H and with its peripheral surface continuous with that of roll r as shown in Fig. 6, which finishes the outer flange t of the tire. The inner flange t' 65 is formed by a spinning-roll α mounted on an oscillating yoke-bar A (see Fig. 1), which is pivoted at α' α'' to the frame of the machine

in such manner that the axis of its oscillation comes in line with the lower inner corner of the spinning-roll, above the upper inner corner of roll S, and distant therefrom about the thickness of the metal blank. So arranged, the spinning-roll can be swung over from the position shown in Fig. 5 to the position shown in Fig. 6, and if this be done 75 gradually while the blank is rotated by the action of the other rolls, the outer projecting edge of the blank will be spun down to the form required for the internal flange t' , as shown in Fig. 6. To enable the attendant to 80 operate the spinning-roll, the yoke-bar A is provided with a lever or handle A' (Fig. 4), by which to rock it on its pivots, and, to aid in holding the spinning-roll in any desired position, the lever A' may be provided with a 85 spring-pawl a^2 engaging in notches in the edge of a curved retaining plate a^3 .

In all prior machines for rolling up the flange t of a wheel-tire, so far as I am aware, a pair of interior and exterior rolls has been 90 used, in which each roll has been made in one solid block fixed concentrically upon its shaft. The result is, that when the rolls are brought together, the rib on the inner roll first touches the tire-blank, before the cylindrical surface of said roll is able to grip the body of the tire-blank against the opposing outer roll, nor will the tire be properly gripped and fed until after the flanging operation is substantially completed, but, on the contrary, 95 it will be held merely by the outer edge of the rib r^2 , at the inner side, and the corners of the groove s' at the outer side. The consequence is, that the tire is liable to be distorted and, in some instances, to be cut or 100 worn through at the flange. In my machine, the body of the tire is first gripped and firmly held between the rolls r S; the feeding is therefore perfectly regular and no distortion can 105 take place; the corners of the groove s' are relieved from the duty of holding the tire and therefore do not tend to cut or wear it, and the rib can be moved gradually toward the groove so as to insure the best conditions 110 of work.

As a matter of mere mechanical construction, I prefer to confine the roll r' and its bearing M between the inner end of the roll r and the outer face of a washer or collar c at the end of the bearing-block e, and to make 115 the block e adjustable longitudinally of the shaft H by means of a collar c' and a set-screw c^2 . These parts can be readily adjusted so as to make the flanging-roll r' run perfectly true, and yet without unnecessary 120 friction. The roll r' should be laterally adjustable, in one direction, to the point where it becomes concentric with the shaft H, as shown in Fig. 6, and, in the other direction, to the point where the outer edge of rib r^2 125 comes in line with the gripping-surface of the feed-roll r , as shown in Fig. 5, any further range of adjustment being unnecessary and, 130 therefore, preferably avoided.

It will, of course, be understood that a mere reversal of the position of the stationary and adjustable roll-shafts—for example, by making the interior roll r and its shaft non-adjustable, and the exterior roll and shaft adjustable, or even by making both of them adjustable, while retaining my independently adjustable ribbed interior roll r' —or arranging the shafts in a horizontal or inclined plane instead of a vertical plane as shown,—would involve mere changes in mechanical details without affecting the character or scope of my principal invention.

Fig. 7 shows the cross-section of a rim-blank, having an inner flange o preliminarily formed upon it near the middle instead of being afterward spun up at the edge, and therefore, for rolling up the outer flange t on this class of rims, the machine should be modified by omitting the spinning-devices, and also by providing in roll r a peripheral groove o' to accommodate the interior flange o , as illustrated in Fig. 8. In such case, also, even if the roll S be made adjustable, it is best to make either the roll r or the guide roll I also adjustable, to facilitate the application of the rim-blank around rolls r I , and the removal of the finished rim therefrom.

Having thus described my invention, what I claim as new, and desire to secure by Letters Patent, is—

1. In a machine for rolling metal rims or tires for car-wheels, the combination of an exterior grooved roll and an interior roll, adapted to grip the tread of the tire between them and feed the tire along, with a ribbed and independently adjustable interior roll adapted to roll up the outer flange of the rim or tire; substantially as described.

2. In a machine for rolling metal rims or tires for car-wheels, the combination of a stationary exterior grooved roll and an adjustable interior roll, adapted to grip the tread of the tire between them and feed the tire along, with a ribbed and independently adjustable interior-roll adapted to roll up the outer flange of the rim or tire; substantially as described.

3. In a machine for rolling metal rims or tires for car-wheels, the combination of an exterior grooved roll and an adjustable interior roll, adapted to grip the tread of the

tire between them and feed the tire along, with a ribbed interior roll, adjustable both with and independently of the plane roll, and adapted to roll up the outer flange of the rim or tire; substantially as described.

4. In a machine for rolling metal rims or tires for car-wheels, the combination of an exterior grooved roll and an interior plane roll, adapted to grip the tread of the tire between them and feed the tire along, a ribbed and independently adjustable interior roll adapted to roll up the outer flange of the rim or tire, and a rocking spinning-roll adapted to turn down the inner flange of the rim or tire; substantially as described.

5. In a machine for rolling metal rims or tires for car-wheels, the combination of an exterior grooved roll, an interior roll fixed to its shaft, and an interior ribbed roll, of an annular form, encompassing said shaft and laterally adjustable with relation thereto; substantially as described.

6. In a machine for rolling metal rims or tires for car-wheels, the combination of the shafts G H and their rolls S r r' , with the adjustable sash E controlling the position of shaft H and its roll r , and the adjustable bearing M controlling the position of roll r' ; substantially as described.

7. In a machine for rolling metal rims or tires for car-wheels, the combination of the shafts G H and their rolls S r r' , with the adjustable sash E controlling the position of shaft H and its roll r , and the adjustable bearing M , supported by the sash E , and controlling the position of the roll r' ; substantially as described.

8. In a machine for rolling metal rims or tires for car-wheels, the combination of the shaft H , the roll r , the adjustable support E and its operating device E' the roll r' and its independently adjustable bearing M mounted upon the support E , and the levers M' M^2 mounted and connected as described and provided with an operating-device N ; substantially as described.

W. E. WILLIAMS.
